(57) **CLAIM**

The ornamental design for a precious stone cut large corner crown design having 41 facets, as shown and described.

DESCRIPTION

FIG. 1 is a top plan view of a precious stone cut large corner crown design having 41 facets showing my new design;

FIG. 2 is a side view; and,

FIG. 3 is a bottom plan view.

The broken line showing of the pavilion of a gemstone is included for the purpose of illustrating environmental matter and forms no part of the claimed design.

Any facets that may be visible through the transparent precious stone are shown for the sake of clarity.
